ABSTRACT: A rotary engine of the alternating piston type comprising a main rotor and subrotor. The main rotor and subrotor are connected by a system of eccentrically mounted linkage means and gear means for converting the relative alternating motion of the main rotor and subrotor into a clockwise rotating force of the main rotor.

ROTARY ENGINE

The present invention relates to an internal combustion engine and particularly to a rotary type internal combustion engine.

The conventional internal combustion engines are substantially used in such type that a piston is moved in a reciprocating motion in a cylinder, but such type permitting the piston to reciprocate has such disadvantage that it vibrates excessively. From above reason various rotary type internal combustion engines have been devised.

In the usual rotary engines, however, the shapes of the rotor and the cylinder containing the same are complicated and difficult to be made up, or their construction or structure is excessively complicated in most cases. A perfect engine has not yet been devised.

The first object of the present invention is to take out a rotary force from explosive force at its maximum.

The second object of this invention is to provide a rotary engine constructed with the parts of simple shapes easy to be worked in comparison with the well-known rotary engines.

The third object of this invention is to provide a rotary engine, the structure of which is simpler and its assembly and adjustment are also easier than those of the well-known rotary engine.

These objects are carried out by combinations and actions of individual parts according to the present invention, and their embodiments will become apparent with the accompanying drawings and by detailed explanation described below.

Modifications and changes in relation to the details of the structure will be contained in the claims described below.

FIG. 1 is a front view cutting longitudinally the main body of the rotary engine according to the present invention.

FIG. 2 is a side view of the same.

FIG. 3 is a longitudinally sectional side view taken along the line 3-3 in FIG. 1.

FIG. 4 are longitudinal section side views showing each process.

FIG. 5 is a longitudinal section front view showing another embodiment according to the present invention.

FIG. 6 is a longitudinal section side view taken along the line 6-6 in FIG. 5.

FIG. 7 are longitudinal section side views showing each process.

The rotary engine according to this invention consists of a cylindrical main body 13 having both sidewalls 11 12, a main rotor 14, a subrotor 15, a suction valve 16 and the like. The main rotor 14 is fixed to a main shaft 17 passing through the center of the main body 13 and is made up to be a circle cut off in its part to decrease weight. To the main rotor 14 is formed a concave portion 19, which reaches from the outer peripheral surface thereof to the surface of the main shaft 17. A front surface 20 and a rear surface 21 of the concave portion 19 are a plane passing through the center of the main shaft 17 and extending along the radial directions, respectively, and both sidewalls 22 are also a plane perpendicular to the centerline of the main shaft 17, respectively. The subrotor 15 is fitted into the concave portion 19, and the inside of the subrotor 15 is of an arced face 23 coinciding with the outer periphery of the main shaft 17 exposed in the concave portion 19 and the outer peripheral surface 24 of the subrotor 15 is an arced face coinciding with the inner peripheral surface of the main body 13. The both sidewalls 25 of the subrotor 15 are formed to be plane, thereby they are close together with the both sidewalls 22 of the concave portion, and the front surface 26 and the rear surface 27 are made up to be a plane passing through the center of the main shaft 17 and on the front surface 26 are formed concave portions 28, 29.

On the rear surface of the subrotor 15 is mounted a bearing 30, in which the front end of a joint 31 is connected to be rotatable by means of a shaft 32. In the concave portion 19, also a shaft 33 is mounted to be located at the rear position of the subrotor 15 and to be rotatable, and the rear end of said joint 31 is fitted around a shaft 34, formed eccentrically at its

center, to be rotatable. Both ends of the shaft 33 are fitted into both side holes 35 of the main rotor 14 to be rotatable, and one end of the shaft 33 hardly protrudes beyond the side face of the main rotor 14, while another end protrudes beyond the surface of the main rotor 14. To the end portion of said projecting shaft 33 is mounted fixedly a gear 36, which is meshed with a gear 37 fitted idly around the main shaft 17.

Between the inner face of the sidewall 11 in the main body 13 and the main rotor 14 is formed a space 18, in which the gears 36 37 and the like are contained. At the outside of the main rotor 14 provided with the gear 37 and so, a gear 38 engaged with the gear 37 is mounted to be rotatable with a shaft 39 which is fixed to rotor 14. In the inner face of the sidewall 11 is fixed an internal gear 40 concentric to the shaft 17, and with the internal gear 40 is meshed said gear 38. Thus, when the main rotor 14 revolves, the gear 38 revolves on its axis in engaging with the internal gear 40 and at the same time revolves round the main shaft together with the main rotor 14 to rotate the gears 37 36 and then the shafts 33 34, thereby the subrotor 15 oscillates against the main rotor 14 through the joint 31.

At the outside of a suction port 43 mounted to the upper part of the main body 13 is positioned a valve casing 41, in which a rotatable suction valve 16 is arranged in parallel to the main shaft 17. Said suction valve 16 is of a cylinder, in one part of which a notch 42 is formed. Into the valve casing 41 is inserted a suction pipe 43', and when the notch 42 of the suction valve 16 stretches over both the inner end of the suction pipe 43', opened into the valve casing 41, and the suction port 43, the suction pipe 43' and the suction port 43 communicate together. One end of a shaft 45' of the suction valve 16 protrudes beyond the valve casing 41, and to said shaft 45' end is fixed a gear 46', which is meshed with a gear 47 fixed to the main shaft 17, thereby the suction valve 16 is connectively driven to revolve it one revolution every one revolution of the main rotor 15.

Each gear ratio of said gears 36, 37, 38 and the internal gear 40 is determined in such rate that the subrotor 15 oscillates two times against the main rotor 14 during one revolution of the main rotor 14.

To the main body 13 are mounted an exhausting port 44 and an ignition plug 45 besides said suction port 43 and then are installed usually necessary parts in the internal combustion engine, such as a generator 48 revolved with the main shaft, a carburetor, a free wheel and the like, and the main shaft 17 is served as a driving shaft (output). Thus, by utilizing volume change of the space between the main rotor 14 and the subrotor 15 are carried out such actions as suction, compression, combustion and exhaustion. Such actions are illustrated as follows:

FIG. 4 I shows a situation close to an end of the suction process. At the position of the end of the suction process in FIG. 4 IV, the space volume between the main rotor 14 and the subrotor 15 is at its minimum, and during revolution of the main rotor 14 from said position to that in I, revolution of the subrotor 15 is delayed to increase the space *a* gradually, so that pressure in the space *a* turns negative (low). During this time the space *a* communicates with a groove 46 formed at the inner face of the main body 13, said groove 46 communicates with the suction port 43 and the notch 42 of the suction valve 16 communicates with both the suction pipe 43' and the suction port 43, so that mixture gas of air with fuel mixed through the carburetor communicating with the suction pipe 43' is sucked into the space *a*.

Process between I and II is a compressive one. Since when the main rotor 14 located at I is revolved somewhat, the space *a* is closed with the inner face of the main body 13 and at the same time the revolution of the subrotor 15 is increased and then the space *a* is decreased, the mixture gas contained in the space *a* is compressed therein.

At the end of the compressive process in II, the space *a* is at its minimum. In this moment, high voltage is applied to the ignition plug 45 located at such position to produce an electric

spark, so that the compressive gas in the space a is ignited and rapidly burnt (exploded).

The pressure owing to expansion of the combustion gas consists of both a force P_1 giving a clockwise revolution to the main rotor 14 and a force P_2 giving an anticlockwise one to the subrotor 15 as shown in II. The force P_2 gives the shaft 33 counterclockwise rotation by rotating the subrotor 15 along a counterclockwise direction, and the gear 36 integrated with the shaft 33 is revolved along the same direction, the gear 37, which is meshed with said gear, being revolved clockwise at the outside of the main shaft 17 and the gear 38, meshed with said gear, is revolved counterclockwise. Since the gear 38 is mounted pivotally to the main rotor 14 and is engaged with the internal gear 40 fixed to the main body 13, the gear 38 is revolved counterclockwise and at the same time round the main shaft clockwise along the internal gear 40. Hence, the main rotor 14 is forced to revolve clockwise after all.

Consequently, the forces P_1 , P_2 to be added to the main rotor 14 and the subrotor 15 along the opposite directions convert into a clockwise rotating force of the main rotor 14.

The combustion (explosion) process mentioned above is between processes II and III in FIG. 4, and in process III the space a is again at its maximum, and then between processes III and IV the space a contracts. During such time, a long exhausting port 44 along the periphery, formed to the main body 13, communicates with the space a , so that the burnt gas in the space a is discharged from the exhausting port 44 to its outside as the volume of the space a is contracted, and the space a reaches at its minimum as shown in process IV, and then the next suction process is carried out again.

In another embodiment of FIG. 5 to 7, a cylindrical main body 53 having both sidewalls 51 52 is separated with a separating wall 56 in its inside to one part of which are mounted the main rotor 54 and the subrotor 55. The main rotor 54 is composed of two, and formed as one body at both sides of a boss 58 fixed to the main shaft 57 passing through the center of the main body 53.

The subrotor 55 is of the same shape as that of the main rotor 54 and two in number and is fixed into space between the side plates 59 60.

Said rotor 55 is contained into the main body 54, and as a matter of convenience in assembly, the side plate 60 is set with screws to the rotor 55 to be removable. Into central holes of the side plates 59 60 are idly fitted the main shaft 57, and an arced surface 61 at the inside of the rotor 55 slides round the outer periphery of the boss 58 of the rotor 54. Consequently, the rotor 55 can be revolved against the rotor 54 in serving the main shaft 57 as a center.

The side plates 59 60 of the rotor 55 are in slide contact with the inner face of the sidewall 51 of the main body 53 and the inner face of the separating wall 56, and the both sides of the rotor 54 are also in slide contact with the inner face of the side plates 59 60. The outer peripheral face of each rotor 54 55 is in slide contact with the inner peripheral face of the main body 53, the front and the rear surfaces of each rotor 54 55 being composed of planes passing through the center of the main shaft 57 and extending along the radial directions, and all spaces a_1 , a_2 , a_3 , a_4 formed between the front and the rear surfaces of each rotor 54 55 are utilized to produce power. On the front surface of each rotor 54 55, the concave portion 61' is formed to leave a minimum space even when the front and the rear rotors 54 55 come in close contact.

The boss 62 formed at the outside of the central portion of the side plate 60 of the rotor 55 is idly inserted into the central hole 63 of the separating wall 56 and protrudes beyond the separating wall 56. To the outer end of said boss 62 is fixed a crank 64.

To the main shaft 57 between the separating wall 56 and the side plate 52 is fixed the center of an arm 65, and in space between said arm 65 and the sidewall 52 a gear 66 is mounted to be rotatable to the main shaft 57. Then, said gear 66 is arranged in the neighborhood of the arm 65 and to be unmovable along the axial direction in relation to the main shaft 57.

To one end of the arm 65 is mounted to be rotatable a shaft 67. To the end portion of said shaft 67 is fixed a gear 68 meshed with the gear 66 and to another end of the shaft 67 is fixed a crank 69. A crank pin 70 of this crank 69 and a crank pin 71 of said crank 64 are connected with a joint 72.

To another end of the arm 65 is mounted to be rotatable by means of a shaft 74' a gear 73, which is long toward its axial direction and is meshed with said gear 66 at the part near to the arm 65. To the part adjacent to the sidewall 52 of the inner periphery of the main body 53 is mounted fixedly an internal gear 74, which is meshed with said gear 73 at the part near to the sidewall 52.

To desired parts of the main body 53 are mounted a suction port 75, an exhausting port 76 and an ignition plug, and further are installed usually necessary parts in the internal combustion engine, such as a generator driven with the main shaft, a carburetor, a free wheel and the like.

In this embodiment, four spaces a_1 , a_2 , a_3 , a_4 made up between each rotor 54 55 perform such actions as a suction, a compression, combustion and exhaustion by utilizing their volume change, respectively.

In FIG. 7 I, the volume of the space a_1 is at its minimum, and it is at starting position of the suction process. When the rotor 54 is revolved clockwise by an angle of 60° from said position, the rotor 55 is also revolved clockwise by 30° and the space a_1 is expanded as shown in II. Further, when the rotor 54 rotates clockwise by 60° , the rotor 55 rotates clockwise by 30° , so that the space a_1 is opened at its maximum as in III. Since in the main body 53 within range from the upper end to an angle of 60° rightwards is formed the suction port 75, into the space a_1 being expanded as mentioned above is sucked mixture gas of air with fuel from the carburetor.

Then, while the rotor 54 is revolved by another 60° , rotary velocity of the rotor 55 is increased and it overtakes the rotor 54, and the space a_1 gets into its minimum as in IV. Thus, when the mixing gas is compressed, high voltage is supplied to a plug 77 mounted to the main body 53 to produce an electric spark, and the gas is burnt rapidly (exploded). The combustion gas expands rapidly and spreads out the space a_1 , so that to the rotors 54, 55 are applied forces toward opposite directions. The force to be applied to the rotor 54 permits the rotor 54 to revolve clockwise, while the force to the rotor 55 permits the rotor 55 to revolve counterclockwise. The counterclockwise force to the rotor 55 permits the gear 68 to revolve counterclockwise through the crank 64, the joint 72 and the crank 69. Such revolution is transmitted to the gear 73 through the gear 66 and permits the gear 73 to revolve counterclockwise.

Since the gear 73 having revolved counterclockwise revolves clockwise along the internal gear 74 and permits the arm 65 integrated with the main shaft 57 to revolve clockwise, the pressure of the mixing gas giving the rotor 55 counterclockwise revolution serves to revolve the main shaft clockwise after all.

By expansion of the combustion gas the space a_1 is spread and at the same time revolved clockwise as mentioned above, so that when the rotor 54 is revolved clockwise by an angle of 60° as in V, the rotor 55 is revolved clockwise by 30° and when the rotor 54 is again revolved clockwise by another 60° , the rotor 55 is also revolved clockwise by 30° and the space a_1 gets into its maximum in volume as in VI. While the rotor 54 rotates clockwise from this position by another 60° , revolution of the rotor 55 is increased and volume of the space a_1 is contracted to reach at its minimum state in I.

Meanwhile, since the space a_1 passes the exhausting hole 76, the gas after combustion is discharged.

In other spaced, the same actions are carried out respectively, and every one revolution of the rotors 54 55 occur four combustions. The above embodiment has such advantage that the spaces between individual rotors are entirely utilized.

Then, in each said embodiment suitable devices for preventing gas from leakage are mounted to mutual sliding faces between the main body, the main rotor and the subrotor. In

the present invention, however, each sliding face consists of face contact, so that there is little risk of gas leakage.

Since in the present invention the rotor rotates round the main shaft and the pressure of the combustion gas exerted to the rotors is completely utilized as a revolving force of the main shaft, explosive force of fuel is converted into a revolving force of the main shaft at its maximum limit.

The present invention has such advantages that the rotor is composed of a simple shape having no part difficult to work and the main body is of a cylinder easy to work, and that the whole structure is also simple and their assembly and adjustment are exceedingly easily carried out.

Moreover, in the embodiment it showed that the case in which by utilizing the ignition plug was ignited fuel, but it can be used as a diesel engine provided with nozzles jetting fuel when the mixing gas is compressed without ignition plug to reach at high temperatures. Besides, numbers of the main body or the rotor may be varied according to its object.

I claim:

1. A rotary engine comprising a cylindrical main body having sidewalls; a main shaft rotatably mounted in said sidewalls through the center of said body; a main rotor means adapted to rotate with said shaft; subrotor means revolvably mounted with respect to said shaft and positioned adjacent said main rotor means such that at least one chamber is formed between said main rotor means and said subrotor means; suction means

for introducing fuel into said chamber; means for igniting said fuel and for causing said rotor means to rotate in one direction around said shaft and for urging said subrotor means to rotate in the reverse direction around said shaft; and means responsive to the ignition of said fuel and operably connecting said rotor means with said subrotor means for overcoming said urging of said subrotor means in said reverse direction;

5 10 15 20 25 30 35 40 45 50 55 60 65 70 75

for introducing fuel into said chamber; means for igniting said fuel and for causing said rotor means to rotate in one direction around said shaft and for urging said subrotor means to rotate in the reverse direction around said shaft; and means responsive to the ignition of said fuel and operably connecting said rotor means with said subrotor means for overcoming said urging of said subrotor means in said reverse direction; whereby said subrotor means rotates in said one direction; said responsive means comprising a first gear mounted on a shaft rotatable with said rotor means, eccentrically mounted linkage means mounted to rotate with said subrotor means for causing said first gear to rotate in said reverse direction, a second gear mounted to rotate around said main shaft and meshing with said first gear to rotate in said one direction, a third gear mounted on said rotor and meshing with said second gear to rotate around its axis in said reverse direction, and an internal gear mounted on one of said sidewalls and meshing with said third gear.

2. A rotary engine as claimed in claim 1 wherein said subrotor means comprises a single rotor and said at least one chamber comprises a single chamber.

3. A rotary engine as claimed in claim 1 wherein said subrotor means comprises more than one subrotor and said at least one chamber comprises more than one chamber.
